Application June 26, 1947, Serial No. 757,228

4 Claims. (Cl. 200—11)

1

This invention relates to electrical circuit switching means, and more particularly to a movable contact rotary switch adapted to open or close a plurality of circuits in sequence and at a relatively high rate of speed.

The principal object of the invention is to provide a device of this nature having a plurality of single pole contacts which are connected or disconnected in sequence at a rate of several hundred times a minute, the duration of such contacts being closely controlled and means being provided for preventing flutter or bouncing of the contacting members under such conditions of operation.

Another object is to provide a rotary multiple contact switch which may be made of very light materials suitable for use in guided projectiles and similar applications.

These and other objects and advantages will be further apparent from the attached drawing which forms a part of this specification and from the following description of a preferred embodiment of the invention.

In the drawing,

Figure 1 is a longitudinal sectional view of a multiple contact switch embodying the invention.

Figure 2 is a transverse sectional view on an arc represented by section line II—II of Figure 1.

Figure 3 is a transverse sectional view on an arc represented by section line III—III of Figure 1.

Figure 4 is an end vertical sectional view on line IV—IV of the arrangement shown in Figure 1.

Referring to the drawing, reference numeral 18 designates generally a base to which is secured a bracket 11 carrying a bearing 12 for shaft 13, which may be driven through coupling 14 by means of a motor or other prime mover, not shown.

An insulating board 15, which forms a main support for one group of the contacting elements to be described, is suitably secured to base 10 and is provided with a circular opening 16 on one side of which is a concentric annular recess 17. A plurality of circumferentially spaced fixed contacts, in this case designated by members 18, extend through the insulating board 15, the inner ends of contacts 18 projecting outwardly into recess 17. An annular disc 19, preferably of a spring metal such as phosphor bronze, is secured by screws 20 to board 15 to overlie the recess 17 and the contact faces of members 18. In this embodiment a plurality of radial slots 21 are formed in disc 19 to provide generally trape-

zoidal cantilever spring fingers opposed to contacts 18 and spaced therefrom the desired distance to be out of contact therewith.

A rotor generally designated 23 is secured to shaft 13 to be concentric with the annular disc 19 and contact members 22. An insulating bushing 24 on rotor 23 serves to electrically isolate the several parts which are secured thereto. A roller 25 is supported on bushing 24 by a flexible radial member 26 to overlap the inner ends of contact fingers 22 and is adjustable by means such as screw 27 to be moved toward or away from the plane of said contact fingers. In this example, roller 25 is illustrated as being a small ball bearing assembly. On the opposite side of the radial flange of bushing 24 is a disc 28 carrying a radially extending cam generally designated 29 which is opposed to roller 25 on the opposite side of the plane of spring contact members 22. A recess 30 is provided along the leading portion of cam member 29 so that roller 25 will be effective to displace a single spring finger 22 toward the cam member thereby also closing the contact between that finger and its corresponding contact member 18. The trailing face 31 of cam 29 is more nearly in the normal plane of members 22 so that after a finger 22 is displaced by roller 25 the transition between the recess 30 and the trailing face 31 will be effective positively to move that spring finger back to its normal or disconnected plane. Desirably, the trailing face 31 is of such a circumferential dimension that it provides a "dwell" surface which acts to damp out vibrations which may have been set up in spring finger 22 by virtue of its initial deflection under roller 25 and its subsequent return to a normal position.

If this were not provided the spring finger would normally oscillate and finally return to its released position at a rate depending upon its natural period and internal damping. It is normally impracticable to so design the length and width of the fingers 22 to produce sufficient spring action to overcome their own natural inertia to follow the deflecting means, in this case the roller 25, so that the cam 29 with its two surfaces just described acts positively to restore the contact element to its normal plane without flutter or undue time lag.

In order to adjust the circumferential relation between roller 25 and the several parts of cam 29, it is desirable to provide means such as slots 32 and screws 33 connecting bushing 24 with the cam follower disc 28 (Figure 4).

Referring again to the drawing, specifically

Figures 2 and 3, the action of roller 25 upon a given contact finger 22 to urge it toward or against cam 29 is illustrated by the first of those figures. Figure 3 is a sectional view taken on the arc of contact members 18 and illustrates how only one of the spring fingers 22 is deflected at this point from its initial position, in this case to complete the contact between plate 16 and a given member 18, by the combined action of the roller and cam just described.

Although the present arrangement illustrates a multiple contact switch in which the contacts are normally open and are closed sequentially by the rotation of rotor 23, it is obvious that a simple reversal of parts would provide the opposite action, namely where the contacts were normally closed and opened in sequence by the action of the rotor 23, roller 25 and cam 29. Similarly the individual contact fingers 22, represented in this example as being formed by slots in a unitary plane annulus of spring sheet metal could equally well be discrete or separate segments secured to a plane insulating base such as plate 16. It is also apparent that, if a longer contacting time is desired without modifying the circumferential dimensions of fingers 22, roller 25 and cam 29, adjacent groups of the fixed contacts 18 could be shunted by suitable connectors. Also, the relative position of the slots in the annulus could be reversed to its outer periphery, with a corresponding reversal of the roller and cam location.

Under certain conditions of relatively low speed operation it has been found that certain of the advantages of the present invention can be obtained without the use of the cam member, particularly if the natural period of the spring fingers is chosen so that adequate contacting action can take place under the influence only of the roller or initial deflecting means for the contact devices.

In conclusion, it will be understood that this invention comprehends broadly a multiple contact switching mechanism characterized by a plurality of coplanar contacting members in combination with a first continuously moving means for deflecting said contact members in sequence in one direction and a second continuously moving means, displaced circumferentially with respect to the first means, for deflecting the contact members in the opposite direction independently of the natural frequency of the individual contact members acting as cantilever springs. Under certain circumstances outlined above, the second continuously moving contact deflecting means just mentioned may be omitted. Although a single example of this invention is illustrated, it is to be understood that numerous changes and modifications could be made in addition to those suggested above without departing therefrom and

all such as are within the scope of the appended claims are embraced thereby.

We claim:

1. A circular multiple contact switch comprising a plurality of coplanar flexible contact fingers comprising radial segments formed in a unitary plane annulus of spring metal, a corresponding plurality of contact points opposing said fingers, a continuously rotating means adapted positively and sequentially to move said fingers in one direction relative to said contact points, and a follower means circumferentially spaced from said first means and on the opposite side of said fingers to move said fingers in the opposite direction relative to said contact points and independently of the vibration characteristics of said fingers.
2. A switching mechanism of the type described characterized by a plurality of coplanar contacting members, a first continuously moving means for sequentially deflecting said contact members in one direction and a second continuously moving means for subsequently deflecting said contact members in the opposite direction, said second-named means being provided with a dwell surface to damp vibration of said contacting members due to said deflections.
3. A circular multiple contact switch comprising a plurality of coplanar flexible contact fingers, a corresponding plurality of contact points opposing said fingers, a continuously rotating roller adapted positively and sequentially to move said fingers in one direction relative to said contact points, and a cam follower means circumferentially spaced from said roller and on the opposite side of said fingers, said cam having a recessed face opposite said roller followed by a raised face in its direction of rotation to move said fingers in the opposite direction relative to said contact points and independently of the vibration characteristics of said fingers.
4. A multiple contact switch according to claim 3 with the addition of means for adjustably positioning said cam circumferentially with regard to said roller.
